UNITED STATES PATENT OFFICE.

OSKAR JUNGHANS, OF SCHRAMBERG, GERMANY, ASSIGNOR TO SOCIETA ANONIMA
ARTURO JUNGHANS, OF VENICE, ITALY.

MECHANICAL TIME FUSE.

Application filed March 13, 1924. Serial No. 699,030.

To all whom it may concern:

Be it known that I, OSKAR JUNGHANS, a citizen of the German Republic, residing at No. 134 of Gaishaldenerstrasse, Schramberg, 5 Germany, have invented certain new and useful Improvements in Mechanical Time Fuses, of which the following is a specification.

My invention relates to a mechanical time-10 fuse provided with a percussion fuse and which is commonly called a compound fuse, and the object of my invention is to provide a safety device in connection with said fuse for the purpose of preventing the charge 15 of the projectile from being prematurely ignited while the latter is still within the gun or ordnance or during its early flight through the air.

Safety-devices are, generally speaking, 20 known in fuses of this kind. The invention provides a specifically new means for the purpose which is of very reliable action; the said means comprising a barrier disk inserted between the carrier or support of the 25 fulminating cap or primer and the igniting charge and adapted to turn about a pivot. Preferably I provide in the said disk a transmitting member such as an explosive pellet which normally lies in a safe position, but, 30 upon firing, moves together with the disk when the latter swings or turns under the centrifugal action exerted upon it during the flight of the projectile, so as to assume a position in line with the open igniting 35 charge and in communication with the fulminating cap, so that the charge cannot ignite except when the disk has turned upon firing owing to centrifugal action during the flight of the projectile through the air.

40 In the accompanying drawing forming part of this specification I have shown by way of example an embodiment of my invention. In the drawing:

Figure 1 is a vertical axial section of the 45 compound fuse with the top-cap removed;

Figure 2 is a section taken on the line 2—2 of Figure 1 and

Figure 3 is a section taken on the line 3—3 of Figure 2.

50 The fuse illustrated in the several figures combines a mechanical time fuse having a clockwork and a percussion fuse having an impact rod or pin projecting into the open air from the top-cap, not shown. As the 55 general construction of a compound fuse of

the kind is commonly known, detail description thereof is not deemed necessary.

In the lower part of the main body of the fuse a recess *a* is provided for the reception of a centrifugal barrier constituted by a 60 disk *b* mounted on a pivot *c* fixed in the top plate *l* of the igniting charge container *n*, the movability of the disk, however, being limited as will hereinafter be explained more 65 in detail.

The disk *b*, separately illustrated in Figure 3, is provided with a bore or hole in which the transmitting member, such as a charge or pellet *d* of readily ignitable nature (picric acid or the like) is embedded. 70 The disk *b* is mounted intermediate between the two parts containing the fulminating cap *e* and the igniting charge *f*, respectively; that is to say between the top plate *l* of the container *n* and the main body of the fuse in 75 which the cap *e* is located, from which, as usual in fuses of the kind, a detonating or firing duct or channel (not shown) in said main body leads to a point in vertical alignment with a hole *l*¹ in the top plate *l* of the 80 container *n*.

Normally, that is to say prior to firing the projectile, the disk *b* has a position of rest in which the hole or the transmitting charge or pellet *d* therein is displaced with relation to the hole *l*¹ in the top-plate *l* of the container *n* and the mouth of the said channel of the main body. In Figure 2 the mouth of the firing channel is indicated by the letter *e*¹ and the disk *b* is shown 90 in this figure in its normal or safe position (full lines) and in its ready position (dotted lines). It will be seen that in the former position the cap *e*, inclusive of the firing channel, and the igniting charge *f* 95 are separated from each other through the disk *b* since the hole or the pellet *d* therein is out of line.

The disk *b* is secured in the said normal or safe position by means of a pin *g* engaging in a recess in the disk and maintained in engagement by means of a so-called centrifugal lever *h* against the action of a spring *i* coiled about the pin *g*. The provision of a securing means of this type is in itself old 10 and needs no detailed description. As usual, the lever *h* is controlled by a spur gear *j* of the clockwork so as to not be released and free to swing out of engagement with the pin 11 *g* through centrifugal action except after the

clockwork has been actuated for a predetermined period of time, as will be readily understood by those skilled in the art.

Supposing the clockwork has run down subsequent to firing the projectile, the lever *h* will turn through centrifugal action imparted thereto by the revolutions of the projectile whereby the pin *g* will be released and the spring *i* permitted to raise the pin out of engagement with the disk *b*, so that the latter will also be free to turn under centrifugal action and move from its safe position—full lines—to the ready position—dotted lines—in Figure 2. As hereinbefore stated the hole or the pellet *d* in the disk is, in the latter position, in line with the opening *b* of the igniting charge covering plate *l* and with the mouth *e* of the firing channel leading to the fulminating cap *e*. Consequently on impact the rod or pin *m* will cause the firing pin *k* to be brought into firing contact with the cap *e*, whereupon the ignition of the charge *f* takes place through the firing channel with the mouth *e*, the pellet *d* and the opening *b*. In fuses of this kind, the firing pin *k* usually is provided with a safety device or detent of its own which is released at a proper time in a known manner.

Though I have described with great particularity of detail the illustrated embodiment of my invention, yet it is not to be understood therefrom that the invention is limited to the particular construction and arrangement shown, it being understood that changes in the form, proportion, size, and minor details may be made within the scope of the claims without departing from the spirit or sacrificing any of the advantages of the invention.

What I claim is:—

1. In a fuse for shells, the combination of a fuse body having a firing channel; an igniting charge container attached to the fuse body and having an opening at its top in line with the firing channel; firing mechanism; a pivotally-mounted barrier interposed between the container top and the channel mouth and provided with a hole, said barrier tending to assume automatically, under the action of centrifugal force when the shell is in flight, a position in which its hole directly alines with said container opening and channel mouth; a

detent normally engaging said barrier to hold it out of such position; and clockwork normally holding said detent in such engagement but releasing it automatically after a predetermined interval of flight.

2. In a fuse for shells, the combination of a fuse body having a firing channel; an igniting charge container attached to the fuse body and having an opening at its top in line with the firing channel; firing mechanism; a pivotally-mounted barrier interposed between the container top and the channel mouth and provided with a hole, said barrier tending to assume automatically, under the action of centrifugal force when the shell is in flight, a position in which its hole directly alines with said container opening and channel mouth; a spring-loaded pin normally engaging said barrier to hold it out of such position; and clockwork normally engaged with said pin to maintain its engagement with the barrier, but releasing it automatically after a predetermined interval of flight, thereby to enable the pin to disengage the barrier under the action of its loading spring.

3. In a fuse for shells, the combination of a fuse body having a firing channel; an igniting charge container attached to the fuse body and having an opening at its top in line with the firing channel; firing mechanism; a pivotally-mounted barrier interposed between the container top and the channel mouth and provided with a hole, said barrier tending to assume automatically, under the action of centrifugal force when the shell is in flight, a position in which its hole directly alines with said container opening and channel mouth; a spring-loaded pin having its inner end normally engaged in a recess in the barrier to hold the latter out of such position; and clockwork including a member normally engaging the outer end of the pin to maintain the engagement of its first-named end in said recess but withdrawn automatically from engagement with said pin after a predetermined period of operation of the clockwork consequent upon firing of the shell.

In testimony whereof I affix my signature.

OSKAR JUNGHANS.
